(57) **CLAIM**

The ornamental design for a mosquito killer lamp, as shown and described.

DESCRIPTION

FIG. 1 is a top perspective view of a mosquito killer lamp design showing my new design.

FIG. 2 is a front view of a mosquito killer lamp.

FIG. 3 is a rear view of a mosquito killer lamp.

FIG. 4 is a left side view of a mosquito killer lamp.

FIG. 5 is a right side view of a mosquito killer lamp.

FIG. 6 is a top view of a mosquito killer lamp.

FIG. 7 is a bottom view of a mosquito killer lamp; and, FIG. 8 is a bottom perspective view of a mosquito killer lamp.

The broken lines depict portions of the mosquito killer lamp that form no part of the claimed design.
